US00D520012S

(12) **United States Design Patent** (10) **Patent No.:** **US D520,012 S**
(45) **Date of Patent:** **** May 2, 2006**

(54) **CONNECTOR FOR DATA CONVERSION**

(75) Inventors: **Atsushi Nishio**, Tama (JP); **Yoshinori Ohta**, Tama (JP); **Masaaki Hayashi**, Tama (JP)

(73) Assignee: **Mitsumi Electric Co., Ltd.**, Tokyo (JP)

(**) Term: **14 Years**

(21) Appl. No.: **29/223,249**

(22) Filed: **Feb. 14, 2005**

(30) **Foreign Application Priority Data**

Nov. 15, 2004 (JP) 2004-034785

(51) **LOC (8) Cl.** **14-02**

(52) **U.S. Cl.** **D14/433; D13/147**

(58) **Field of Classification Search** ..... 439/367, 439/352, 620, 247, 248, 263, 378, 37, 701, 439/76.1, 541.5, 74; D14/433, 435, 356, D14/357, 432; D13/147; 174/65 R; 361/601, 361/686, 730, 752, 796; 333/25, 24 R, 32, 333/33; 335/202
